CLAIM

The ornamental design for the lock for lockable media storage container, as shown and described.

DESCRIPTION

FIG. 1 is a side elevation view of the lock for lockable media storage container showing our new design.

FIG. 2 is a top plan view of FIG. 1.

FIG. 3 is a bottom plan view of FIG. 1.

FIG. 4 is a right side elevation view of FIG. 1; the left side being a mirror image thereof.

FIG. 5 is a side elevation view of an alternative embodiment of the lock for lockable media storage container showing our new design.

FIG. 6 is a top plan view of FIG. 5.

FIG. 7 is a bottom plan view of FIG. 5; and,

FIG. 8 is a right side elevation view of FIG. 5; the left side being a mirror image thereof.

The unshaded portions of FIGS. 2 and 6 are understood to form no part of the claimed design.
